[57] CLAIM

The ornamental design for a treatment table extension frame for spinal traction, as shown.

DESCRIPTION

FIG. 1 is a front, right-hand perspective view of a treatment table extension frame for spinal traction, showing my new design;

FIG. 2 is a front elevational view thereof;

FIG. 3 is a rear elevational view thereof;

FIG. 4 is an elevational view of one side, the opposite side elevational view being substantially a mirror image thereof;

FIG. 5 is a top plan view thereof; and,

FIG. 6 is a bottom plan view thereof.
